RIBBON CURLER

Pasquale L. Cerone, Dewitt, N. Y.

Application November 1, 1949, Serial No. 124,839

3 Claims. (Cl. 93—1)

1

This invention has to do with apparatus for automatically and continuously curling paper ribbon. It has become customary for retail stores to wrap gift packages in ornamental paper, or sheet material, and to adorn the package with bows, or ornaments, formed out of curled, colored, paper ribbon. Usually the curling of the paper ribbon is accomplished by the clerk by drawing the ribbon between the thumb and a blade, such as the blade of a pair of scissors. This consumes a considerable amount of time, especially during the holiday season, and the procedure does not result in a uniform curl, or a uniform arrangement.

This invention has as an object a compact motor driven device embodying a structure which functions automatically to put a uniform, helical curve in the ribbon, the ribbon being fed through the device automatically from a supply at a fast rate, whereby the uniformly curled ribbon is produced at the rate of several yards per minute.

The invention has as a further object a device of the type referred to embodying cutting mechanism for automatically cutting the curled ribbon into uniform pieces, or sections, of any desired length.

The invention consists in the novel features and in the combinations and constructions hereinafter set forth and claimed.

In describing this invention, reference is had to the accompanying drawings in which like characters designate corresponding parts in all the views.

Figure 1 is a side elevational view of a device embodying my invention, the housing enclosing the operating mechanism being removed.

Figure 2 is a front elevational view of the structure shown in Figure 1.

Figure 3 is an exploded view showing the curling bar, friction member and supporting bracket in perspective.

The device consists of a suitable frame which may be in the form of a plate 10 mounted upon a base 11. A stud 12 is mounted on the plate 10 in proximity to the upper end thereof to support a supply of uncurled ribbon, such as a spool 13. The spool is sleeved over the stud for free rotation thereon and is retained in place by a fastener 14. The ribbon is advanced from the supply by a pair of feed rollers 15, 16. The roller 16 is journaled upon a stud 17 secured, at one end, to an arm 18 journaled on a stud 20 extending from the plate 10. The roller 15 is fixed to the end of a shaft 21 extending outwardly

2

from the face plate and which is rotated by a motor 22 secured to the opposite side of the plate 10. The roller 16 is yieldingly urged into engagement with the roller 15 by tension spring 23 secured at one end to the arm 18 and at its opposite end to a stud 24 projecting from the plate 10.

The ribbon is fed between a curling bar 25 and a friction member 26. One edge of the bar 25 is beveled, as at 27, and the members 25, 26, are detachably secured to a bracket 28, a portion of which is formed with elongated slots 30 for the reception of mounting screws 31 provided with thumb nuts 32. The bracket 28 is mounted on the plate 10 with the bar 25 arranged in juxtaposition to the feed rolls 15, 16, and parallel to the axes thereof. The feed rolls function to draw the ribbon from the supply between the bar 25 and the friction member 26 and over the beveled edge 27 thence downwardly discharging the ribbon in a vertical helix as shown in Figure 1. The bar 25 and the friction member 26 are apertured to receive screws 35 which extend through a plate 36 and thread into the bracket 28. Compression springs 37 are interposed between the heads of the screws 35 and the plate 36, whereby the frictional engagement between the plate 25 and the member 26 may be adjusted, and which adjustment determines the tension of the ribbon as it is drawn between these members and over the beveled edge of the curling bar.

The slots 30 and bracket 28 provide adjustment of the position of the curling bar relative to the rollers 15, 16, whereby the angle of the ribbon drawn over the beveled edge 27 relative to the friction member 26 may be varied.

In the arrangement shown, the ribbon is guided between the curling plate and friction member 26 by a roller 38 journaled upon the stud 24. If the ribbon supply is in the nature of a long spool, as illustrated, it is preferable to feed the ribbon downwardly and about stationary pins 39, 40, and upwardly about the roller 38 around roller 41 downwardly about the roller 38. This arrangement permits the ribbon to travel back and forth the length of the spool 13 while being unwound therefrom, the lateral movement of the ribbon being reduced as it travels about the pins 39, 40, so as the ribbon passes over the rollers 38, 41, there is no lateral movement, and the ribbon is guided in a straight line between the curling plate 25 and friction member 26.

The bows or ornaments formed from the curled paper are usually formed from a plurality of

pieces of the curled tape. At the present time in making these by hand operation, the clerk more or less guesses at the lengths of the pieces of curled material, with the result that the individual pieces used in forming the ornamental piece are not uniform, and the completed ornamental pieces are not uniform. I provide mechanism for severing the curled strip into uniform lengths. A structural arrangement for accomplishing this, consists of a guide member 45 mounted on the plate 10, as by screws 46. This guide member is formed with a vertically extending aperture 47 to receive the curled ribbon 49. The member 45 is formed with a passage 50 extending transversely of the aperture 47 and in which there is slidably mounted a shear blade 51. This blade is connected to the plunger 52 of a solenoid 53 by a pin 54. The solenoid 53 is energized periodically by any conventional time switch indicated at 55 supplied with current through conductors 56. The blade 51 is yieldingly urged outwardly in the position shown in Figure 1, by a tension spring 57. As the time switch 55 periodically energizes the relay 53, the shear moves transversely across the path of the curled portion 49 severing it into desired lengths.

What I claim is:

1. A device for continuously and automatically curling a paper ribbon comprising a frame, means for supporting a supply of uncurled ribbon, a pair of power operated feed rolls having their axes extending horizontal in parallel relation, a bar mounted horizontally on the frame above the bight of said feed rolls, a friction plate, means yieldingly urging said bar against one side of said plate, the upper edge of said bar being beveled outwardly and downwardly from said friction plate, said feed rolls being cooperable to advance the ribbon upwardly between said friction plate and bar and downwardly over the upper beveled edge of the bar, and means for adjusting the position of said bar and friction member toward and from the vertical plane passing through the bight of said feed rolls.

2. A device for continuously and automatically curling a paper ribbon comprising a frame, means carried by the frame for supporting a supply of uncurled ribbon, a roll journalled in

the frame with its axis extending horizontally, a bar arranged above said roll and intermediate said roll and the supply of uncurled ribbon and said bar extending parallel to the axis of the roll, 5 a pressure roll, means yieldingly urging said pressure roll toward said other roll, a friction member positioned against one side of said bar, a tension member mounted at each end of the bar, said tension members being independently adjustable 10 to vary the pressure between said bar and friction member, power means operable to effect rotation of said rolls and said rolls constituting feed rolls operable upon such rotation to draw said ribbon upwardly between said bar and friction member and reversely over the edge of the bar and discharge the curled ribbon downwardly. 15 3. A device for continuously curling a paper ribbon comprising a frame, means carried by the frame for supporting a supply of uncurled ribbon, 20 a pair of power operated feed rolls journalled in the frame for frictionally engaging opposite sides of the ribbon, a bar having a beveled edge arranged intermediate said supply and said rolls and extending parallel to the axis thereof, a friction member positioned against one side of the bar, said feed rolls being operable to draw the ribbon from said supply between said bar and friction member and reversely over the beveled edge of the bar and discharge the ribbon vertically, and means adjustable to vary the frictional engagement between said friction member and the ribbon.
